UNITED STATES PATENT OFFICE.

JAMES ROBERT STEELE, OF OWEGO, NEW YORK.

ANTICREEPER.

1,245,056.

Specification of Letters Patent. Patented Oct. 30, 1917.

Application filed March 23, 1916. Serial No. 87,165.

To all whom it may concern:

Be it known that I, JAMES ROBERT STEELE, a citizen of the United States, and a resident of Owego, in the county of Tioga and State of New York, have invented certain new and useful Improvements in Anticreepers, of which the following is a specification.

The object of my invention is to provide a simple and specially efficient device to prevent creeping or longitudinal movement of railroad rails.

In the drawing illustrating a preferred embodiment of my novel anti-creeper:

Figure 1 is a rear elevation of the anti-creeper applied to a rail, before locking, the rail being shown in section, and a tie in elevation, and the yoke of the anti-creeper being partly broken away.

Fig. 2 is a view similar to Fig. 1 showing the wedge driven home and locked by the coöperation of the deformable tail with the opening of the yoke.

Fig. 3 is a section on the line 3—3 of Fig. 2, and

Fig. 4 is a perspective view of the wedge. The device includes a yoke 1 having suitable ends 2 and 3 to take over the edges of the rail base, and a transverse under-rail portion 4, the upper surface of which is separated from the bottom of the rail base and inclined in the direction of its length relatively thereto. Within this space and upon the wedge-way thus provided is a wedge 5, which is driven transversely of the rail to secure the anti-creeper in place. It will be understood that the device is applied to and removed from the rail laterally, and that the yoke is constructed with sufficient room between the hook ends and body to afford clearance for this purpose, as well as to accommodate the wedge. As is customary, one end, in this instance the end 2 at the higher end of the wedge-way, is more deeply hooked or undercut than the other, this being the end which is engaged first with its edge of the rail base when the device is tilted onto the rail. The wedge is materially shorter than the space included between the rail base at the top, the yoke body at the bottom and the hook-ends at

the sides, and substantially shorter also than the wedge-way whereon it travels. The upper side of the wedge is preferably substantially horizontal, and its engagement with the yoke may be rendered more secure and the driving operation facilitated by forming the lateral portions 6 of the wedge so as to project beyond the lines of the yoke and to extend vertically down at the sides thereof. Manifestly, however, it is not necessary that both sides of the wedge project, and an extent of vertical overlap between the wedge and yoke, which is quite important to prevent relative displacement transverse to the direction of driving, may be secured by specifically different forms.

When the anti-creeper is placed upon the rail and the relatively short wedge driven up and along its wedge-way, the yoke becomes slightly sprung, bringing into play the elasticity of the material and securing a resilient binding action which is especially desirable in a device of this character. The result of this action is not only to cause the ends of the yoke to grip the rail base tenaciously but to lock the wedge against retrograde movement through slight bowing or deflection of the way upon which it must move.

The wedge may be additionally locked against undesired release by means of a deformable rod 7 fitting an opening 8 in the end 3 of the yoke and coöoperating with the rear end of the wedge, to which it may be secured. This opening and also the rod or tail are inclined to the wedge-way when the parts of the anti-creeper are assembled in readiness for driving, as shown in Fig. 1. In the present instance they are represented as being horizontal, but obviously the hole might be inclined to the horizontal as well as to the plane of the wedge-way, that is to say the relative inclination could be greater if desired. When the wedge is driven home, as shown in Fig. 2 the tail bends slightly so as to bind with the opening, thereby producing an effective lock rendering it doubly impossible for the wedge to work back as the result of vibration and shocks due to the movement of trains upon the rails.

The tail is most advantageously provided by inserting the end of a short steel rod into the mold wherein the wedge is cast in the process of manufacture, the wedge and tail 5 being thus integrally united and the rod possessing the qualities which its purposes require.

In assembling the wedge and yoke the wedge is tilted on the wedge-way sufficiently 10 to enter the end of its tail in the opening, after which the tail is forced outwardly through the opening by blows or pressure applied to the inner end of the wedge, causing the wedge to take up a position at or adjacent 15 the end 3 as shown in Fig. 1. The assemblage is now tilted onto the rail. The shortness of the wedge permits this to be done, and enables the device to fit rail bases of different sizes. The driving of the wedge 20 in the reverse direction, that is to say, in order to lock the device to the rail, is accomplished by delivering blows upon its outer end. For this purpose a suitable tool may be employed straddling the end of the yoke, 25 or a simple punch may be used, applying the blows toward one side, this being effective since the wedge is guided against lateral displacement.

The removal of the anti-creeper is best 30 accomplished by driving the wedge outward and then tilting the yoke off the rail-base; or it may be effected by striking one or more sharp blows upon the end 2 of the yoke remote from the tail, thereby causing the whole 35 device to spring off the rail.

When in action it will be understood that the anticreeper bears against the rear face 40 of a tie, and being gripped to the rail, the latter cannot move lengthwise relatively to the tie. In Fig. 3 the wedge is shown as abutting the tie, but manifestly the yoke may be the part which abuts, or both may do so.

What I claim as new is:

45 1. An anti-creeper comprising a yoke having hook ends to take over the edges of the rail-base and its connecting body constructed to be separated from the rail-base by clearance and wedging room, the top of said 50 body being formed as a wedge-way sloping lengthwise of the yoke, and a wedge movable transversely of the rail in the space between the bottom of the rail-base and the top of the yoke-body and between the hook 55 ends, the wedge being materially shorter than said space and the wedge-way whereon it travels.

2. An anti-creeper comprising a yoke having hook ends to take over the edges of the 60 rail-base and its connecting body constructed to be separated from the rail-base by clearance and wedging room, the top of said body being formed as a wedge-way sloping lengthwise of the yoke, and a wedge mov-

able transversely of the rail in the space between the bottom of the rail-base and the top of the yoke-body and between the hook ends, the wedge being materially shorter than said space and the wedge-way whereon it travels and projecting laterally therefrom. 65 70

3. An anti-creeper comprising a yoke having hook ends to take over the edges of the rail-base and its connecting body constructed to be separated from the rail-base by clearance and wedging room, the top of said 75 body being formed as a wedge-way sloping lengthwise of the yoke, and a wedge movable transversely of the rail in the space between the bottom of the rail-base and the top of the yoke-body and between the hook 80 ends, the wedge being materially shorter than said space and the wedge-way whereon it travels, the wedge and wedge-way having an extent of vertical overlap preventing relative lateral displacement. 85

4. An anti-creeper comprising a yoke having hook ends to take over the edges of the rail-base and a connecting body separated from the bottom of the rail-base in use, one of said ends being more deeply recessed than the other and the top of said connecting body being formed as a wedge-way sloping lengthwise of the yoke upward toward this more deeply recessed end, and a wedge movable transversely of the rail in the space between the bottom of the rail-base and the top of the yoke-body and between the hook ends, the wedge being materially shorter than said space and the wedge-way whereon it travels. 95 100

5. An anti-creeper comprising a yoke adapted to embrace the rail base and having a wedge-way inclined to the plane of the rail base, the yoke being further provided in one end with an opening, a wedge movable 105 on the wedge-way transversely of the rail, and a deformable locking rod cooperating with said opening.

6. An anti-creeper comprising a yoke adapted to embrace a rail base and having 110 an opening in one end and a wedge-way inclined to the plane of the rail base, a wedge movable on the wedge-way transversely of the rail, and a cast-in rod projecting from the rear end of the wedge and fitting said 115 opening to produce a bending lock on the driving of the wedge.

7. An anti-creeper comprising a yoke to embrace the rail base and a wedge to be driven between the yoke and rail base, the 120 wedge having a tail and the yoke an opening wherewith the tail binds.

8. An anti-creeper comprising a yoke having ends to take over the edges of the rail base and an inclined wedge-way extending 125 lengthwise of its transverse under-rail portion, and a wedge formed to overlap said wedge-way.

9. An anti-creeper comprising a yoke having inturned ends to hook over the rail-base and a transverse body portion dropped below the position of the rail-base and formed
5 with interior clearance room permitting it to be applied to the rail laterally of the latter and with an inclined wedge-way sloping lengthwise of the body portion and transversely with respect to the rail, and a relatively short wedge operative upon said 10 wedge-way in the space between the body portion of the yoke and the bottom of the rail.

JAMES ROBERT STEELE.
